UNITED STATES PATENT OFFICE

118,768

DESIGN FOR A GAS RANGE CABINET

Charles T. Donnelly, Culver City, Calif.

Application June 5, 1939, Serial No. 85,345

Term of patent 3½ years

To all whom it may concern:

Be it known that I, Charles T. Donnelly, a citizen of the United States, residing at 8790 Washington Boulevard, city of Culver City, in the county of Los Angeles and State of California, have invented a new, original, and ornamental Design for a Gas Range Cabinet, of which the following is a specification, reference being had to the accompanying drawing, forming part thereof.

Figure 1 is a perspective view of a gas range cabinet in closed position showing my new design, and

Figure 2 is a perspective view from the same angle with the top opened and also the oven door open.

The other side of the cabinet is substantially like that shown.

I claim:

The ornamental design for a gas range cabinet, as illustrated and described.

CHARLES T. DONNELLY.
